UNITED STATES PATENT OFFICE.

MAX J. MILZ, OF TAFT, CALIFORNIA.

CASING-CUTTER.

1,107,822.

Specification of Letters Patent. Patented Aug. 18, 1914.

Application filed January 22, 1914. Serial No. 813,734.

To all whom it may concern:

Be it known that I, MAX J. MILZ, a citizen of Austria, residing at Taft, in the county of Kern, State of California, have 5 invented certain new and useful Improvements in Casing-Cutters; and I do hereby declare the following to be a full, clear, and exact description of the invention, such as will enable others skilled in the art to which 10 it appertains to make and use the same.

The present invention is directed to improvements in casing cutters, and has for its object to so construct a device of this character that the same can be lowered in a well 15 casing and manipulated to cut the casing at the desired point.

A further object of the invention is to provide a casing cutter so constructed that the cutting disks can be set with their peripheries disposed inwardly of the bounding 20 surface of the cutter for insertion in the casing, after which they may be moved outwardly during the reciprocation of the rod.

With these and other objects in view, this 25 invention resides in the novel features of construction, formation, combination and arrangement of parts to be hereinafter more fully described, claimed and illustrated in the accompanying drawing, in which:

30 Figure 1 is a side elevation of the device when being lowered in the casing. Fig. 2 is a similar view, showing the device in its cutting position in the casing. Fig. 3 is a sectional view taken on a vertical plane. 35 Fig. 4 is a detail perspective view of one of the supporting blocks for the cutting disks. Fig. 5 is a sectional view on line 5—5 of Fig. 1. Fig. 6 is a similar view on line 6—6 of Fig. 2. Fig. 7 is a similar view on line 40 7—7 of Fig. 2. Fig. 8 is a similar view on line 8—8 of Fig. 1.

Referring to the drawing, the numeral 1 designates the body of the cutter, the same 45 consisting of upper and lower sections 2 and 3, respectively, the lower section being swivelly connected to the upper section 2 by the head 4, as clearly shown in Fig. 3 of the drawing. Passing through the sections 2 and 3 is a rod 5, the lower end of which is 50 provided with a head 6, said head having one of its sides provided with an inclined shoulder 7, the purpose of which will appear later. The upper end of the rod is provided with the threaded extension 8 for 55 engagement by the usual drill rod (not shown). Slidably mounted on the rod 5

is a collar 9 from which depend fingers 10 which slidably engage the slots 11, formed in the section 2. The fingers 10 are provided with grooves 12, said grooves being slightly 60 inclined and are adapted to be engaged by the ribs 13 formed upon the blocks 14 which revolvably support the cutting disks 15. It will be noted that as the fingers 10 move downwardly during the operation of the tool 65 the blocks 14 will be gradually moved outwardly so that the cutting disks will sever the casing 16 upon continued rotation of the section 2 during which time the section 3 remains stationary in the casing. The blocks 70 14 are pivotally mounted in the recesses 17 formed in the upper end of the section 2 and are caused to return to their inoperative position by the coil springs 18, which have one of their ends connected to the blocks 75 19 and their other ends fixed in the sockets 19 also formed in the section 2, and as clearly shown in Fig. 5 of the drawing.

The rod 5 is provided with a longitudinal 80 groove 20 which is slidably engaged by the rib 21 formed in the bore of the section 3, said rib serving to prevent accidental rotation of the section 3, but permitting the rod 5 to freely reciprocate during the cutting operation. The rod 5 is also provided with 85 a spiral groove 22 which is slidably engaged by the rib 23 formed in the bore of the section 2, the pitch of said groove being such that upon downstroke of the rod about five-eighths of a revolution of the section 2 will 90 be obtained. It is also obvious that upon the upstroke of the rod 5 about five-eighths of a revolution of the section 2 will be obtained. Thus it will be seen that the section 2 will rotate alternately back and forth, and 95 as the cutting disks 15 are supported by said section, the same will cut during the rotation of the section in either direction.

In Fig. 1 of the drawing there is shown a block 24, which is provided with a serrated face 25, said block being also provided with a beveled rib 26 which is designed to engage the inclined shoulder 7 formed in the head 6 so that said block when moving downwardly will be moved laterally, thus moving from under the projection 27 carried by the lower end of the section 3, and when this occurs the section 3 moving downwardly will cause the plates 28 to bite into the interior surface of the casing, owing to the fact that the lower end 105 of the section and inner faces of the plates 110

are inclined. When the plates 28 are engaged with the interior of the casing the section 3 is held both against vertical and rotary movement.

5 When the tool is lowered in the well, and the parts are in the position as shown in Fig. 1 the teeth of the block 24 will grip the inner face of the casing upon a sharp jerk upwardly being imparted to the rod 5, 10 whereupon said block will move downwardly and laterally so that the projection 27 will disengage the same, thus causing the plates 28 to move outwardly and grip the casing. Fixed to the section 3, and diametrically opposite the projection 27 is the upper end of the bowed spring 29, the lower end of which has fixed thereto a block 30 which when the tool is being lowered in the casing rests in the groove 31 formed 15 in the head 6, but as soon as the plates 28 have gripped the casing the block 30 will move inwardly so that when the head 6 is moved upwardly, and at the time when it is desired to remove the tool from the casing, 20 said block will engage the upper surface of the head 6. Thus it will be seen that upon the tool being moved upwardly the plates 28 will move inwardly so as to disengage the inner surface of the casing, after 25 which the tool can be easily removed. The bowed spring 29 also serves to yieldably force the teeth of the block 24 into engagement with the casing so that when a jerk is imparted to the tool the teeth of said 30 block will grip the casing, thus locking the section 3 in the casing. Slidably connected to the lower ends of the plates 28 are wedge members 32, which have their upper surfaces inclined, as at 33, for engaging the 35 inclined surfaces 34 formed upon the lower ends of the plates 28.

From the foregoing description it will be seen that when the section 3 has been locked in the casing at the proper position reciprocatory movement is imparted to the rod 5, whereupon the section 2 will be compelled to rotate alternately back and forth, thus causing the cutting disks 15 to sever the casing. A cushioning spring 35 encircles the rod 5 and has one end bearing 40 against the upper surface of the collar 9 and its other end engaged by the disk 36. This spring serves to receive the impact of

the blows from the head 37 of the rod should the same in its downward movement engage the disk 36.

The casing cutter herein described is especially designed for operation by a cable through which the device is reciprocated and lowered.

What is claimed is:—

1. A casing cutter comprising upper and lower sections, a rod passable through the sections, cutting disks supported by the upper section, means carried by the rod for partially rotating the upper section first in one direction and then in the other direction, and means for holding the lower section stationary in the casing.

2. A casing cutter comprising upper and lower sections, a rod passable through the sections, a collar carried by the rod, fingers depending from the collar, said fingers having inclined grooves formed therein, blocks pivotally supported by the upper section, cutting disks carried by the blocks, said blocks having ribs for slidably engaging said grooves, grooves formed in the upper section for slidably receiving the fingers, said blocks being adapted to move outwardly gradually as the fingers move downwardly in said grooves, and means for alternately rotating the upper section back and forth.

3. A casing cutter comprising upper and lower sections, a rod passable through the sections, a head formed upon the lower end of the rod, a projection carried by the lower section, wedge plates slidably connected to the lower section, a block slidably mounted upon said head for engaging the projection, said block being adapted to engage the casing and adapted for movement downwardly and laterally to disengage the projection to release the lower section which when moving downwardly will move the plates outwardly to lock the lower section to the casing, and means carried by the rod for alternately rotating the upper section back and forth during the reciprocation of said rod in the upper and lower section.

In testimony whereof, I affix my signature, in the presence of two witnesses.

MAX J. MILZ.
